UNITED STATES PATENT OFFICE.

ALFRED F. MORELL, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

THREAD-PLACER.

1,259,656.

Specification of Letters Patent. Patented Mar. 19, 1918.

Application filed August 18, 1916. Serial No. 115,609.

To all whom it may concern:

Be it known that I, ALFRED F. MORELL, a citizen of the United States, residing at Worcester, in the county of Worcester and 5 State of Massachusetts, have invented a new and useful Thread-Placer, of which the following is a specification.

This invention relates to a thread placer for use in looms in which the weft is automatically replenished before the weft supply in the running shuttle is entirely exhausted.

In this type of looms, after the operation of the transfer mechanism, a portion of weft 15 extends from the selvage toward the shuttle box, and it is necessary that this portion of weft should be immediately severed and removed before it can be woven into the cloth. For this purpose, a temple thread 20 cutter is used and it is the object of my present invention to provide a device which shall coöperate with this thread cutter to insure the positive cutting of this outgoing weft.

With this object in view, one feature of 25 my invention consists in the provision of a thread placer carried by the lay and adapted to be advanced relatively to the reed after the weft transfer, such movement positively 30 presenting the outgoing weft to the action of the temple thread cutter. In the preferred form of my invention the thread placer is actuated indirectly from the trans- 35 ferrer arm, said arm being effective to move an actuator to operative position. Provision is also made for withdrawing said actuator after the operation of the thread placer. This latter mechanism is herein shown as under the control of the feeler mechanism and 40 as adapted to withdraw the actuator after the second operation of the thread placer. I also provide for the retraction of the thread placer as the shuttle and lay reach their extreme forward position, thereby 45 avoiding engagement with the temple or temple thread cutter.

My invention further relates to certain arrangements and combinations of parts which will be hereinafter described and more 50 particularly pointed out in the appended claims.

A preferred form of my invention is shown in the drawings in which—

Figure 1 is a side elevation of my im-

proved thread placer and the operating 55 mechanism therefor, certain parts of the loom being shown in section;

Fig. 2 is a top plan view of parts of the mechanism shown in Fig. 1, taken along the 60 line 2—2 in said figure;

Fig. 3 is a top plan view of additional mechanism shown in Fig. 1, taken along the line 3—3 in that figure;

Fig. 4 is a detail sectional view taken 65 along the line 4—4 in Fig. 3, and

Fig. 5 is a longitudinal sectional view of the spring plunger which positions the actuator.

Referring to the drawings, I have shown a temple 10 of the usual form mounted upon 70 the breast-beam 11 and provided with a movable thread cutting element 12. The lay is indicated at 13 supported upon the usual sword 14 and provided with the usual reed 15 and hand rail 16. The shuttle 17 is indicated in its position on the lay.

The thread placer comprises an arm 20 secured to a shaft 21 in position to swing between two adjacent dents of the reed 15. The shaft 21 is mounted in bearings 22 and 80 23 formed on a bracket 24 secured to the sword 14. A coil spring 25 is fixed at one end to the bearing 22 and at the opposite end to a collar 26 adjustably secured to the shaft 21, by means of which the tension upon 85 the shaft may be adjusted. Stops 27 and 28 coöperate to limit the backward movement of the thread placer 20. A cam arm 30 is fixed to the opposite end of the shaft 21, and supports a double-faced cam 31 90 through which the thread placer is actuated.

I will now describe the mechanism for moving the cam 31 and actuating the thread placer. A portion of a stationary weft magazine 35 is shown in the drawings, said magazine being provided with a rock shaft 36 mounted in fixed bearings on the magazine and connected to mechanism not shown from which the rock shaft receives motion on any alternate beat of the lay if the feeler mechanism calls for a change in filling. For further illustration and a more complete description of this magazine mechanism reference is made to the patent to Ryon, No. 1,030,748 issued June 25, 1912, the shaft 36 100 105 of this application corresponding to the shaft 36 of the patent.

An actuator 40 is mounted upon a fixed

pivot 41 carried by the magazine 35, and is provided with an extension 42 having notches 43 and 44 adapted to coöperate with a spring plunger 45 by which means the actuator may be retained in either operative or inoperative position. The details of the spring plunger are clearly shown in Fig. 5, the plunger being mounted in a fixed sleeve 46 carried by the magazine.

10 A stud 47 is carried by the actuator 40 and is movable with the actuator into the path of travel of the cam 31. For moving the actuator from its normal inoperative position to its operative position I provide a lug 50 upon the outer face of the regular transferrer arm 51. As this transferrer arm moves downward to eject a substantially exhausted weft carrier, the actuator is also moved downward until the 15 stud 47 occupies the position shown in dotted lines in Fig. 1, in which position it is retained by the spring plunger 45.

As the lay continues its forward movement, the stud 47 engages the cam 31 and 20 swings the thread placer forward to carry the outgoing weft into the path of the temple thread cutter 12. As the lay continues to move forward, the cam 31 passes beyond the stud 47 and the thread placer is retracted by the spring 25 before it engages the temple 10 or its thread cutter 12.

This operation of the thread placer is once repeated after which the actuator 40 is removed to its inoperative position. The 25 devices for thus removing the actuator comprise a rod 52 threaded into a head 53 pivoted at 54 to a member 55, said member being loosely mounted on the shaft 36 and being actuated by a rod 56 preferably formed 30 integral with the usual rocker 58 carried by the shaft 36. The rod 56 is freely slideable longitudinally through an opening in the member 55. The threaded rod 52 at its lower end is offset to form a shoulder and 35 engages a lug 60 upon the back side of the actuator 40.

The rock shaft 36 and the rocker 58 receive movement before the operation of the transferrer arm 51, and the rod 52 is thus 40 lowered to permit movement of the actuator 40 by the transferrer arm. The actuator remains in operative position until the shaft 36 and rocker 58 are restored to their inoperative positions, at which time the actuator 45 is also restored to its inoperative position. I have thus provided a thread placer which is positively actuated by the trans- 50 ferrer mechanism and which is controlled

in its actuation by the weft detecting mechanism of the loom. The placer is arranged 60 to present the thread positively to the temple thread cutter while at the same time it is itself withdrawn before engagement therewith can occur.

Having thus described my invention it 65 will be evident that other changes and modifications can be made therein by those skilled in the art without departing from the spirit and scope thereof as set forth in the claims, and I do not wish to be otherwise limited to the details herein disclosed.

70 What I claim is:—

1. In a loom, a lay having a reed, a temple thread cutter, a thread placer movable with the lay and positioned adjacent said cutter, means to momentarily advance said placer relatively to the reed as the lay moves forward at the time of transfer, and means effective to retract said placer before said lay reaches its extreme forward position.

2. In a loom, a lay having a reed, a thread placer, means to momentarily advance said placer relatively to the reed on each of two successive forward beats of the 85 lay, and means to retract said placer before each forward beat is completed.

3. In a loom, a lay having a reed, a thread placer mounted on the lay and movable relatively to said reed, a transferrer arm, and 90 connections between said placer and said transferrer arm whereby said transferrer arm controls the actuation of said placer.

4. In a loom, a lay, a thread placer mounted thereon, a cam movable therewith, 95 an actuator effective through said cam to give said placer an operative movement, means to move said actuator to operative position relatively to said cam, means to thereafter return said actuator to inoperative position, and a spring effective to move said cam and placer in the reverse direction, said cam permitting such reverse movement of said placer during the continued forward movement of the lay.

100 5. In a loom, a thread placer, an arm secured thereto having a double-faced cam thereon, a cam stud to actuate said cam, an arm supporting said stud, a spring plunger to hold said arm in a selected position, and 105 feeler-controlled mechanism for moving said arm to operative and inoperative positions.

In testimony whereof I have hereunto affixed my signature.

ALFRED F. MORELL.
